UNITED STATES PATENT OFFICE

LOUIS ALFRED RAMSDEN, OF MANCHESTER, ENGLAND

DESIGN FOR AN ELECTRIC LAMP

Application filed February 2, 1933, Serial No. 47,082, and in Great Britain September 28, 1932.
Term of patent 7 years.

To all whom it may concern:

Be it known that I, LOUIS ALFRED RAMSDEN, a British subject residing at Manchester, county of Lancaster, England, have invented a new, original, and ornamental Design for Electric Lamps, of which the following is a specification, reference being had to the accompanying drawing, forming part thereof.

The figure is an elevation of an electric

lamp showing my new design which consists in forming the lower bulb with a spherical lower surface and conical sides and an upper bulb with a spherical upper surface and conical sides.

I claim:—

The ornamental design for an electric lamp as shown and described.

LOUIS ALFRED RAMSDEN.
